SIGNORS OF ONE-THIRD TO PLATT BROTHERS AND COMPANY LIMITED, OF OLDHAM,
ENGLAND

METHOD OF AND MEANS FOR WEIGHTING THE SLIP ROLLS FOR LAPS IN TEXTILE MACHINES WHEREIN THE MATERIAL ACTED ON IS FORMED INTO LAPS

Application filed June 5, 1931, Serial No. 542,282, and in Great Britain August 23, 1930.

These improvements have to do with textile machinery of that class in which the material acted on is formed into laps on delivery, as for instance, amongst other apparatus, may be mentioned exhaust opener lap-machines, cylinder opener lap machines, scutcher lap machines, but the improvements apply to any textile machine in which a lap is produced.

10 The invention concerns an improved method of and means for weighting the lap, or more strictly for weighting the slip rolls upon which the laps are wound.

In the best known type of lap weighting arrangement, the weighting is wholly effected by a braking system or friction combination, which includes a friction wheel and a pivoted loaded lever with foot pedal, the friction combination requiring to impart a 20 very considerable friction to be effectively operative and to ensure the required yardage in the lap. The friction wheel is compounded with a small pinion on a sleeve, and this small pinion, through carrier wheels and 25 pinions, actuates a shaft with pinions, which gear with the vertically arranged loading rack bars. The shaft mentioned, passes freely through the axis of the friction wheel and its compounded pinion, and has fixed upon 30 it the known hand wheel. This hand-wheel is requisite in order to permit the operative to work the rack bars to elevate the same when a lap is fully wound, which can only be done when an operative puts his foot on 35 the treadle of the braking lever. To turn the hand-wheel with the braking lever on, is almost an impossibility for an operative. If the braking lever be released, the gearing can of course be turned by hand to the requisite extent and the braking lever re-engaged.

In practice, this brake or friction loading is well known to be unsatisfactory and troublesome and to produce uneven laps, and to 45 cause breakage of slip rolls and racks, as the actuation of the friction (being necessarily heavily set) can only occur at intervals when the lap is sufficiently consolidated as to overcome the total heavy "friction" and force the 50 slip roll to lift the "heads" of the loading

racks, whereupon a period of relief is obtained. As a result, laps are never wound under a uniform and definite load, but rather the friction is only overcome at uncertain periods, and then the rack bars lift momentarily under the imposed strain.

Our improved method has to do with a system by which laps (or rather the slip rolls therefor) can to the extent of about half the load be dead-weighted by constant or adjustable dead weights or other weighting loads, so arranged, that they furnish a uniform weighting to or in connection with the provided vertical rack bars, and so far as they are concerned provide always the same 60 constant and uniform dead weight load which is imposed on the lap being wound. Further, the method makes requisite the power to be able to mechanically lift up the rack bars still higher when a lap is fully 65 wound, and to maintain same in that position, and this we do by the provision of a friction or brake mechanism with lightly loaded foot treadle of holding capacity to resist the load of the gear and dead weighting 70 such friction supplying the other half of the load, and further we fashion the hand-wheel, the friction wheel and a small pinion as one revolvable group, which, as the lap is wound, is slowly rotated by the lifting of rack bars 75 operating through a train of gear, and this revolvable group can be easily turned even 80 without disengaging the foot-treadle which bears on the friction wheel.

The means involved are such as will function mechanically according to this improved method.

In order to further explain the invention we hereafter describe an appropriate form 90 of mechanism which operates in accordance with the method set forth, and the said mechanism is illustrated in the accompanying drawing, wherein:

Fig. 1 is a side elevation showing the mechanism applied to a lap forming apparatus, only so much of an actual apparatus being shown as is requisite for a proper explanation of the invention.

Fig. 2 shows a front view partly in sec- 100

tion of Fig. 1 omitting some of the gearing. Fig. 3 is a partial plan view.

Fig. 4 shows a developed diagram of the gear, etc., but with certain of the gear, etc. turned into a horizontal plane for simplicity of illustration.

We use vertical rack bars 1, 1, which are properly guided in any known or suitable way. These rack bars 1, 1 are formed with 10 or have applied thereto the known heads 2, which may be provided with the known anti-friction rollers. The rack bars 1, 1 are fashioned with or have fixed thereto slotted brackets 3 or projections to seat or support 15 any series of longitudinal weights such as the weights 4, which have end projections to socket in the slotted brackets 3. The weights 4 are shown as extending between the two slotted brackets 3, so as to equally load the 20 rack bars 1, 1. If desired, the rack bars 1, 1 may be separately and equally loaded.

There is a cross-shaft 5 with two rack pinions 6, 6 keyed on it, the pinions engaging the rack teeth on the vertical rack bars 1, 1, and, 25 mounted and keyed on a sleeve or support 7 at the operative end of the shaft 5, is a small spur pinion 8, a friction wheel 9, and a hand wheel 10. The small spur pinion 8 gears into a larger pinion 11 keyed on the end of 30 an intermediate shaft 12. A further small pinion 13 keyed on the other end of the intermediate shaft 12 gears with a large pinion 14 compounded with a small pinion 15 which rotates on a fixed stud 16, the small 35 pinion 15 actuating, through a carrier wheel 17, one of the pinions 6 on the rack pinion shaft or cross-shaft 5, the said pinion 6 gearing with the teeth on one of the vertical rack bars 1.

40 As a consequence, with the described construction and arrangement of mechanism, the same dead weight load which is about half the total load is at all times on the rack bars 1, 1, and the slip rod (marked *r*) has 45 only to lift the rack bars 1, 1 with attached weights by exerting the same upward pressure, whilst, as the rack bars lift, they turn through the train of gears, the combined small spur pinion 8, friction wheel 9, and 50 hand wheel 10, such group being uniformly and slowly rotated so as to overcome the holding friction which supplies the other half of the total loading.

When the vertical rack bars 1, 1 require to 55 be raised, the operative has only to turn the hand-wheel 10, which it is found can be done even without disengaging the lightly weighted treadle lever 18, pivoted at 19 and having the adjustable weight 20. If the lightly 60 weighted treadle lever 18 is disengaged, after removal of a wound lap, and re-insertion of a slip rod *r*, the gears allow the dead-weight loaded rack bars 1, 1 to run slowly down.

The friction device used by us supplies 65 about half the weighting effect and holds the

rack bars 1, 1 in any position, at any time, and the dead-weight supplies the other half of the weighting effect.

By our invention, the weighting is made definite and constant to any desired weight 70 load from start to finish, by the use of ascertained dead weights, supplying half the loading effect whilst the friction supplies the other half and so laps can be produced which are perfectly uniform in thickness or 75 evenness.

The weights can be added to or deducted from as may be required from time to time, the drawing showing three weights of a long 80 bar-like type with notched ends and which sit, one over another, in the brackets 3, but we are not in any way restricted to such a weighting arrangement, as this is capable of much variation.

The friction block on the foot-treadle 18 is marked 22.

We claim:

1. In a device of the kind described, a pair of vertically extending and vertically movable rack bars, a slip rod extending between and carried by the upper parts of said rack bars, weight supporting means on said rack bars below said slip rod, and weights carried by said weight supporting means.

2. In a device of the kind described, a pair of vertically extending and vertically movable rack bars, a slip rod extending between and carried by the upper parts of said rack bars, weight supporting means on said rack bars at the bottom ends of said rack bars, and removable weights carried by said weight supporting means.

3. In a device of the kind described, a pair of vertically extending and vertically movable rack bars, a slip rod extending between and carried by the upper parts of said rack bars, confronting pockets on said rack bars open at their tops, and weight bars extending between said rack bars and having their ends received in said pockets.

4. In a device of the kind described, a pair of vertically extending and vertically movable rack bars, a slip rod extending between and carried by the upper parts of said rack bars, confronting pockets on said rack bars open at their tops, and weight bars extending between said rack bars and having their ends received in said pockets, said pockets being located at the lower ends of said rack bars.

In testimony whereof we have signed our names to this specification.

HENRY WILKINSON.
ARTHUR ROE.
